G. SCHONSTEINER ET AL

SUCTION SUPPORT FOR BOOTBLACK STANDS AND THE LIKE

Filed Sept. 30, 1922

Gottlieb Schonsteiner,
Thomas E. Michael,

By *Henry J. Doolan* Attorney

UNITED STATES PATENT OFFICE.

GOTTLIEB SCHONSTEINER AND THOMAS EDWARD MICHAEL, OF PITTSBURGH, PENNSYLVANIA.

SUCTION SUPPORT FOR BOOTBLACK STANDS AND THE LIKE.

Application filed September 30, 1922. Serial No. 491,519.

To all whom it may concern:

Be it known that we, GOTTLIEB SCHONSTEINER, a citizen of Switzerland, and THOMAS EDWARD MICHAEL, a citizen of the 5 United States, both residing at Pittsburgh, in the county of Allegheny and State of Pennsylvania, have invented a new and useful Suction Support for Bootblack Stands and the like, of which the following is a 10 specification.

This invention is a semi-automatic foot support.

One of the objects of the invention is to provide a stand for use in establishments, 15 where boots, shoes and the like are cleansed and polished. Another object of the invention is to provide a device wherein certain discomfitures attending shoe-shining are eliminated, i. e. the slipping off of the foot. 20 Another object is to provide a device that is positive in its functioning, economical to manufacture and operable by anyone.

The invention will be best understood by referring to the following detailed description used in connection with the accompanying drawing, and the scope of the invention will be particularly pointed out in the appended claims.

In the accompanying drawing:—

30 Figure 1 is a vertical elevation of the invention. Figure 2 is an end view. Figure 3 is a sectional view. Figure 4 is a plan view.

Referring to the drawing in detail, 10 35 denotes a base or support, and 11 a hollow casing or cylinder, to which is attached a resilient member 12, used for holding the foot in a comfortable position. On casing or cylinder 11 at its upper end is a check- 40 valve 14 used to prevent air from entering, but permitting its escape from the cylinder. Operable within casing 11 is a piston consisting of two parts shown at 16. The lower piston-head has a boss 17 rigidly 45 affixed thereto, in which operates a connecting lever 18. Between piston heads 16 are positioned leather cups 15, for creating a suction within casing 11, suitable means being provided for securing the same in place. 50 To the rod or lever 18 is attached a handle 19. At the bottom of base 10 is a lock 20. To the upper end of casing 11, the foot support 21 is shown fastened by means of a thread at T. In the base 10 and extending

upward is slot 13 to permit of operating the 55 lever 18 and handle 19.

In operating the device, the foot is placed upon the stand so as to cover the opening 12, thus preventing air from entering the suction chamber, or cylinder. By pulling 60 down the handle 19 while the foot is so positioned, a suction effect upon the foot is obtained, which holds it securely, and prevents the person polishing the shoe from accidentally displacing the said foot. To release the foot, the operator unlocks the handle 19, raises the same, forcing air out through check valve 14, destroying the suction, and leaving the foot free to be removed at will. 65

70 While the invention has been described in connection with foot rests for shoe blacking stands, it is not limited to this particular use, but comprehends other uses within the scope of the appended claims.

75 Having thus described our invention what is claimed is:—

1. A device of the class described comprising a stand having a cylinder at one end provided with a thread, a foot-support 80 forming a cup and having a thread complementary to the first thread, and a resilient member having an opening communicating with said cylinder, and a piston working in said cylinder. 85

2. A device of the class described comprising a stand having a cylinder at one end provided with a thread, a foot-support provided with a cup having a thread complementary to the first thread to close the end of said cylinder, and a positively operating suction means co-operating with said foot-support to prevent slipping of a foot placed thereon. 90

3. A device of the character described comprising a stand slotted in one end, a foot-rest, a suction device co-operating therewith, a lever functioning in said slot and connected to said suction device, and an automatic release valve positioned in one end of said 100 stand. 95

4. A device of the character described comprising a stand slotted in one end, a foot-support of the character described consisting of a cylinder on said stand, suction-producing means operable within said cylinder, a foot-rest having an opening and communicating with said cylinder, a lever func- 105

tioning in said slot and connected to said suction device, and an automatic release valve positioned in one end of said stand.

5. A device of the class described comprising a cylinder open at one end, a foot-rest closing said open end and having an opening therein, and suction-producing means operable within said cylinder, and means located within the opening of said

10 foot-rest to prevent slipping of a foot placed thereon.

6. A device of the character described comprising a cylinder, open at one end, and having a slot at the other in which is operable a functioning element to create a suction within said cylinder, a foot-support having removably affixed thereto a resilient member to co-operate with a suction member.

15 In testimony whereof we have hereunto set our hands.

GOTTLIEB SCHONSTEINER.
THOMAS EDWARD MICHAEL.
